UNITED STATES PATENT OFFICE.

CARL BRAMMING, OF CHICAGO, ILLINOIS, ASSIGNOR TO ACCESSORIES MANUFACTURING CO., A CORPORATION OF ILLINOIS.

CIRCUIT-CONNECTOR.

1,323,821.

Specification of Letters Patent.

Patented Dec. 2, 1919.

Application filed March 29, 1917, Serial No. 158,465. Renewed September 15, 1919. Serial No. 323,998.

To all whom it may concern:

Be it known that I, CARL BRAMMING, a citizen of the United States, and resident of Chicago, county of Cook, and State of Illinois, have invented certain new and useful Improvements in Circuit-Connectors, of which the following is a specification and which are illustrated in the accompanying drawings, forming a part thereof.

10 The invention relates to circuit connectors adapted for use in connection with a wall, such as the dashboard or cowl of an automobile, and is shown as adapted for use with a gage lamp.

15 The objects of the invention are to provide a connector of the plug and socket type in which the socket element is to be securely attached to a support, such as a wall, and the plug element may be held in two positions within the socket, in one of such positions the circuit being closed and in the other being open.

20 A further object is to provide improved means for holding the plug in either of its positions, to prevent harmful vibration of the plug and a lamp carried thereby, while relieving these parts of the jarring action which would be communicated thereto directly from the support as in automobile 25 service.

25 A preferred embodiment of the invention is hereinafter described, and is shown in the accompanying drawings in which—

Figure 1 is an elevation of the connector with a gage lamp and canopy mounted thereon;

Fig. 2 is a longitudinal section of the device; and

Fig. 3 is a detail longitudinal section, partly in elevation.

30 The socket element 10 is provided with a wall plate 11 for convenience in attaching it to a support, not shown. Within the inner end of the socket 10 is fixed a connector plug 12, to which the leading-in wires may be attached and which is provided with spring-advanced contact plungers 13, 14, for engagement by the contact of the plug element 15.

35 The plug 15 is preferably of non-conductive material and has fixed within it a pair of conductors 16, 17, the inner ends of which engage the plunger contacts 13, 14, when the plug is fully inserted. Associated with the 40 outer ends of the conductors 16, 17, are a

pair of plunger contacts 18, 19, adapted to be engaged by the base 20 of a lamp 21 in the usual manner. The plug 15 is fixed within a shell 22 which projects beyond its end and is adapted to receive as a socket the 60 lamp base 20, being provided with suitable means for retaining the lamp, such as the bayonet joint shown.

A helical spring 23, coiled about the plug 15, seats against a shoulder thereon, which 65 in the construction illustrated is the inner end of the shell 22 and reacts, either directly or indirectly, against the end of the socket 10. For the purpose of covering and protecting the spring a sleeve 24 slidingly 70 fits upon the shell 22 and preferably is flanged inwardly at its inner end, as shown at 25, this flange forming a seat for the inner end of the spring.

The socket 10 is provided with a slot 26 75 of the bayonet joint type but of special configuration for coöperating with a pair of studs, as 27, projecting laterally from the plug 15. The slot 26 is substantially U shape, one end opening through the outer 80 end of the socket 10 and the other end being closed and forming a seat for the studs 27. The bowed portion of the slot 26 is recessed in its inner face to form a shoulder or pocket 28 within which the stud 85 27 coöperating therewith may enter, thereby holding the plug 15 in its inner position. Preferably the slot is also provided with a stop shoulder 29 which will arrest the stud 90 when shifted from the inner end of the slot, the position shown in Fig. 3, and aline it with the pocket 28.

When the plug 15 is inserted into the socket 10 the spring 23 is compressed and will hold the studs 27 firmly against either 95 of the slot seats 28 or 29, the latter being the inner end of the slot. The parts are so proportioned that when the studs 27 are seated in the pockets 28 the ends of the conductors 16, 17, are in engagement with the 100 contact elements 13, 14, and the circuit is closed. When the plug is shifted to permit the studs 27 to engage the seats 29 these conductors are out of engagement with the contact elements and the circuit is open. 105

When the plug is entirely withdrawn from the socket the expansion of the spring 23 will force the flange 25 against the studs 27 and the latter will thus prevent the sleeve 110 and spring from being separated from the

plug. When thus separated the plug may be used in connection with another socket, thus adapting it for use with an extension wire and permitting the employment of the 5 lamp as a trouble finder.

When the parts are assembled and occupy the positions shown in Figs. 2 and 3, the lamp is held against injurious vibration by the spring 23 but is, nevertheless, yieldingly 10 supported and thus freed from the violent jarring action which would be communicated to it from the vehicle were the attachment rigid.

While the device is shown as adapted for 15 use in connection with a two line circuit, it is obvious that it may be used with a single line grounded circuit, in which case but one set of contact elements would be required.

I claim as my invention—

20 1. In a circuit connector, in combination, a socket, a contact element within the socket, a plug adapted to enter the socket and interlock therewith in two positions, a contact element carried by the plug and engageable 25 with the socket contact element when the plug is in one of its interlocking positions and being out of engagement therewith when the plug is in its other interlocking position, and a spring surrounding the plug 30 and reacting between a shoulder thereon and the socket.

2. In a circuit connector, in combination,

a plug and a socket telescopically engageable and provided with co-operating contact elements, the socket being provided with a 35 U-shaped slot one end of which opens through the end of the socket wall, the other end of the slot being closed and the bow of the slot being offset inwardly to form a 40 pocket, a stud projecting from the plug and adapted to enter the slot, and a spring surrounding the plug and reacting between the plug and socket.

3. In a circuit connector, in combination, a socket, a plug interfitting the socket and interlocking therewith in two positions, a 45 shell fixed upon and projecting beyond the outer end of the plug and forming a socket for another plug, and a spring reacting between the inner end of the shell and the first 50 named socket.

4. In a circuit connector, in combination, a socket, a plug interfitting the socket and interlocking therewith in two positions, a shell fixed upon and projecting beyond the 55 outer end of the plug and forming a socket for another plug, a spring reacting between the inner end of the shell and the first named socket, and a sleeve slidably mounted on the shell and inclosing the spring having a 60 shoulder forming a seat for the end of the spring.

CARL BRAMMING.
